GUN SIGHT

Walter Falkenhagen, Antigo, Wis.

Application April 14, 1949, Serial No. 1,969

Term of patent 14 years

(Cl. D30—1)

To all whom it may concern:

Be it known that I, Walter Falkenhagen, a citizen of the United States and resident of Antigo, county of Langlade, and State of Wisconsin, have invented a new, original, and ornamental Design for Gun Sight, of which the following is a specification, reference being had to the accompanying drawings, forming part thereof.

Figure 1 is a top plan view of a gun sight showing my new design.

Figure 2 is a side elevation of the same.

Figure 3 is a bottom plan view of the gun sight.

Figure 4 is a front end view of the gun sight; and

Figure 5 is a rear end view of said gun sight.

I claim:

The ornamental design for a gun sight, as shown.

WALT. FALKENHAGEN.
